Inventor,

Charles Franklin Perry,

By Franks Ausman,

Attorney

UNITED STATES PATENT OFFICE.

CHARLES FRANKLIN PERRY, OF HARLINGEN, TEXAS.

CANAL-GATE.

1,333,217.

Specification of Letters Patent.

Patented Mar. 9, 1920.

Application filed February 12, 1919. Serial No. 276,479.

To all whom it may concern:

Be it known that I, CHARLES FRANKLIN PERRY, a citizen of the United States of America, and resident of Harlingen, in the 5 county of Cameron and State of Texas, have invented certain new and useful Improvements in Canal-Gates, of which the following is a specification.

This invention relates to flume or canal 10 gates and particularly to a gate which can be readily applied to or removed from a lock of a flume or canal, the said device being of such a nature that it will be held closed by the force of the water in addition to the 15 mechanical features of construction which causes it to seat in the opening of the lock.

An object of this invention is to provide a lock of the character indicated having a simple and comparatively inexpensive contrivance 20 for receiving a handle or the shank of the handle which is attached to the lock or gate, the said handle projecting upwardly so that it can be manipulated for applying or removing said gate.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a sectional view of a flume or water way with the lock in place; and

Fig. 2 illustrates an end view thereof at the intake end.

In these drawings 5 denotes a hollow member which may be round or any cross sectional configuration, the same having a flange 6 at one end, which flange constitutes in part an anchorage for a loop comprising a strip of material 7 having apertures 8 for the reception of fastenings such as rivets 9 by which it is secured to the flange, the said plate having an outwardly turned portion

forming a loop 10 which is adapted to receive a shank 11 of a handle 12, the said handle being secured to the gate 13 of the canal lock by a metallic strap 14 which may be attached to the gate 13 by fastenings such as rivets 15.

As shown in Fig. 1, of the drawing, the 55 lower part of the handle is cut away to form a shoulder 16 which fits the contour of the outer surface of the gate and the shank of the said handle lies against the outer surface of the flange of the gate and projects there- 60 beyond into the seat therefor carried by the flange 6.

From an inspection of the drawing, it will be apparent that by manipulating the handle and forcing the gate away from the end of the casing 5, the inwardly extending portion of the gate may be made to clear the end of the casing and the shank of the handle may then be lifted from its seat, thus removing the gate and opening the flume or canal, 70 whereas in replacing the gate, the shank of the handle may be applied to its seat and the force of the fluid will hold it in place, although the parts are so fitted together that there is some frictional contact for engage- 75 ment between the inwardly extending portion 17 of the gate and the inner wall of the casing.

While I have shown the gate as being round or circular it is to be understood that 80 it may be square or of other configuration in plan.

I claim—

In a canal gate, a casing having a flange, a strap secured to the flange, a closure for the 85 flanged end of the casing, said closure comprising a plate having a depressed portion fitting in the casing, and a flange over-lying a portion of the flange of the casing, a handle secured to the said closure, said handle 90 having a relatively wide portion terminating in a reduced end, the said reduced end extending over the flange of the closure and into the strap secured to the flange of the casing.

CHARLES FRANKLIN PERRY.
